CHLORINATOR

Robert S. Lucas, Harbor City, Calif., assignor to
Purex Corporation, Ltd., Lakewood, Calif.

Filed June 29, 1970, Ser. No. 23,722

Term of patent 14 years

Int. Cl. D24—02; D23—01

U.S. Cl. D16—2

FIG. 1 is a perspective view of a chlorinator, showing my new design;

FIG. 2 is a front elevated view thereof;

FIG. 3 is a plan view thereof;

FIG. 4 is a side elevation view thereof taken along line 4—4 in FIG. 2; and

FIG. 5 is a rear elevational view thereof.

I claim:

The ornamental design for a chlorinator, substantially as shown.
